UNITED STATES PATENT OFFICE.

CARL R. LINDENBERG, OF COLUMBUS, OHIO, ASSIGNOR TO THE INDESTRUCTO TRUNK COMPANY, OF COLUMBUS, OHIO, A CORPORATION OF OHIO.

WARDROBE TRUNK.

Application filed August 18, 1924. Serial No. 732,647.

To all whom it may concern:

Be it known that I, CARL R. LINDENBERG, a citizen of the United States, residing at Columbus, in the county of Franklin and

5 State of Ohio, have invented certain new and useful Improvements in Wardrobe Trunks, of which the following is a specification.

This invention relates to improvements in 10 wardrobe trunks and has for its primary object the provision of means in a trunk of this character wherein the wardrobe section of a trunk will be braced and straightened so that when the two sections of the trunk 15 are brought into registering relation the locking elements carried by the sections will be properly registered to permit of their convenient and intended cooperation.

In the manufacture of wardrobe trunks 20 it is customary to provide at least one of the sections, commonly known as the wardrobe section, at one end with a hinged top or cover. This section of the trunk is adapted to have mounted therein slideable 25 rods upon which are carried hangers for the suspension and retention of clothes or other articles within the trunk in neat and orderly array. Since the cover of this section is hinged and is movable to an elevated position opening the top of the trunk, it follows 30 that the trunk sides are to some extent left unsupported and weakened because of the absence of an effective transverse tie. This has resulted in the bulging or bowing of 35 the sides when the trunk is permitted to stand open for any length of time, with the result that when it is desired to again lock the two sections of the trunk together, difficulty has been had in causing the locking 40 elements of the trunk to properly register. Therefore, it is the prime object of the present invention to provide the wardrobe section of the trunk with an improved fastening device concealed in a swinging door or 45 closure member which is of such construction that when the door is closed the two sides of the trunk will be joined together and pulled into proper registration, preventing the sagging of the trunk sides as previously 50 noted and enabling the trunk to be properly locked without difficulty.

With these and other objects in view, as will appear as the description proceeds, the invention consists in the novel features of 55 construction, combinations of elements and

arrangements of parts hereinafter to be fully described and pointed out in the appended claims.

In the drawings:

Figure 1 is a perspective view of a wardrobe trunk constructed in accordance with the present invention, 60

Figure 2 is a horizontal sectional view taken through the trunk on the plane indicated by the line 2—2 of Figure 1, 65

Figure 3 is a front elevation disclosing my improved door construction, and

Figure 4 is a vertical section taken on the line 4—4 of Figure 3.

Referring more particularly to the specific details of the invention, the numeral 1 designates a wardrobe trunk in its entirety. This trunk consists of the usual wardrobe section 2 and the drawer containing section 3. These sections are united as 70 usual by means of hinges so that when the trunk is closed the said sections may be united by means of the ordinary locking device 4. When in use as an article of furniture, the trunk is set on end as shown in 80 Figure 1, and the two sections are opened so that convenient access may be had to the contents of both sections of the trunk. The wardrobe section is formed to include the usual sides 5, a bottom 6 and a hinged top 75 7, which is capable of being swung to assume the elevated position, disclosed in Figure 1 so that when the door 8 of the wardrobe section is swung to assume an open position convenient access may be had to the 85 garments carried upon hangers situated within the wardrobe section. 90

This construction of the trunk is very desirable for the purpose specified, but since the hinged cover or top 7 does not function 95 to support the sides 5 when the top is elevated there exists in the trunk a certain structural weakness which it is the purpose of this invention to overcome. It will be seen that when the top 7 is elevated there 100 is very little support except at the back of the trunk, for the sides 5, which, by reason of the weight of the garments within the trunk and the weight of the trunk itself, have a tendency to spread or bow and to 105 4 when the trunk is again closed.

To overcome this condition I provide the ornamental closure or door 8 with a stiff 110

metallic brace 9 which is riveted or otherwise secured to the frame 10 of the door as at 11. Further, the brace at the hinged edge of the door is shaped to produce one leaf of a hinge 12, the other leaf of said hinge being riveted or otherwise firmly secured to the outer of the sides 5. The brace 9 extends transversely across the door along the rear side of the latter and has its forward end pivotally secured as at 14 to a latch member 15, which is arranged for engagement with a fixed eye or hook 16 provided upon the inner of the sides 5, the outer end of the latch member 15 being formed with a hook shaped extremity 17 designed for cooperation with the eye 16. To operate the latch member, there is provided a pivoted bail or handle 18 formed with upper and lower trunnion shaped ends 19. This bail is positioned within a casing 20 recessed within the frame of the door 8, and the lower trunnion end 19 of the bail has suitably fixed thereto for rotation the latch member 15.

In operation, in order to lock the door 8 in its closed position the latch member is swung to assume the dotted line position disclosed in Figure 2. Then, to lock the door closed the bail 18 is moved from the dotted line position, shown in Figure 2, to the full line position. This causes the latch member to rock about the pivotal axis defined by the lower end of the bail and to enter into hooked engagement with the eye 16 provided upon one of the sides 5. It will be noted that the outer end of the brace 9 is connected to the latch member eccentrically with respect to the pivotal axis of said latch member and that when the latch member is moved from its locking to its unlocking positions or vice versa the brace member will be moved equal degrees of travel across the center line defined by the pivotal axis of the latch member. This results in locking the latch member in either its opened or closed position and retains the

parts secure against accidental dislodgment. It would seem that this construction provides a tie between the sides 5 which will securely hold the sides against bowing or sagging, and in the event that through warping or other causes the said sides do sag or bend slightly, the construction described will then serve to straighten the sides and bring the same into proper relative arrangement necessary in locking the two sections of the trunk together.

From the foregoing it will be seen that the present invention provides a simple and effective structure for uniting the sides of a wardrobe trunk in secured relationship so as to both secure and preserve the original shape of the sides to attain the ends above specified. The construction is concealed in the door 8 and except for the operating member 18 there is nothing present in the structure which is in any way objectionable to the general appearance of the trunk. The door is usually provided with a fabric covering 21 which may be used to conceal the brace 9.

What is claimed is:

1. In a wardrobe trunk, a wardrobe section provided with spaced longitudinal sides, means for uniting said sides adjacent to their outer edge portions, comprising a closure member hinged to one of said sides, a locking device for uniting the free swinging edge of said closure to the other of said sides, and a metallic reinforcement provided in connection with said closure providing a metallic connection for drawing said sides together along their outer edge portions.

2. In a wardrobe trunk, a wardrobe section including a pair of spaced longitudinally extending sides, a swinging closure between the outer edge portions of said sides, and a metallic reinforcement carried in connection with said closure for pulling said sides into aligned relationship.

In testimony whereof I affix my signature.

CARL R. LINDBERG.
